E. J. LIPPS,
 MEANS FOR WRAPPING STRANDS AROUND EACH OTHER,
 APPLICATION FILED OCT. 17, 1916.
1,216,147. Patented Feb. 13, 1917.

UNITED STATES PATENT OFFICE.

EMORY J. LIPPS, OF FOUNTAIN HILL BOROUGH, PENNSYLVANIA.

MEANS FOR WRAPPING STRANDS AROUND EACH OTHER.

1,216,147.

Specification of Letters Patent. Patented Feb. 13, 1917.

Application filed October 17, 1916. Serial No. 126,115.

To all whom it may concern:

Be it known that I, EMORY J. LIPPS, a citizen of the United States, residing at Fountain Hill Borough, in the county of Lehigh and State of Pennsylvania, have invented certain new and useful Improvements in Means for Wrapping Strands Around Each Other, of which the following is a specification.

10 In a co-pending application of Lloyd H. Lipps and myself for a patent for a method of uniting textile strands means has been disclosed for wrapping two strands around each other so as to put a so-called "preliminary second-time" twist therein which would keep the strands together and thus avoid the use of the usual flier in the ensuing second-time twisting or spinning operation, the same consisting of a member over which 20 the strands were drawn in frictional contact therewith and which presented a smooth surface extending crosswise of the line of draft of the strands, and means to effect relative movement as between said member 25 and the strands crosswise of said line. The said member as shown had the form of a cylindrical bar, the round shape of which caused appreciable surface to be presented to the strands so as by frictional action to 30 insure the desired wrapping during the relatively lateral movement. In practice I have found that it greatly improves the wrapping action if in coincidence with the "crown" of the wrapping a groove or other 35 space be provided in the wrapping member so as to extend longitudinally of its acting surface; with such a space present the tendency of the strands to lie side by side and not roll over each other when the tension 40 reaches a certain degree as the result of the wrapping and consequent twisting already produced is eliminated, so that the wrapping may continue to a much further extent than where the space is absent.

45 I now proceed to a more particular explanation of my invention, reference being had to the accompanying drawing, wherein,

Figure 1 is a side elevation, partly in section, of a wrapping means including the 50 present improvement, that part of the means for drawing the strands lengthwise which consists of the receiving spool appearing in side elevation; and

55 Fig. 2 is a front elevation of the wrapping means, the strands in this case appearing magnified.

d is the spool on which the strands are wound. The latter are assumed to be supplied from a source, such as another spool, 60 below spool *d* under a certain amount of tension, the supply spool and tension means not being shown.

The means for causing the wrapping of the strands around each other in the present instance includes the traverse rail *e*, having 65 the notched guide *f* to receive the strands, and the cylindrical bar *m*, and some means (not shown) for causing relative movement as between rail *e* and bar *m* lengthwise thereof, that is, crosswise of the line of draft on 70 the strands.

g is a guide for the strands, projecting from rail *e* below bar *m*, which not only in a measure contributes to the tension and keeps the strands close together (preferably 75 by being set obliquely—Fig. 2), thereby to insure the wrapping action, but in actual frictional contact with an appreciable portion, measured circumferentially, of the surface of the bar, as from A to B in Fig. 1. 80

The surface portion A—B of the bar is divided by a groove C midway thereof into two parts, which are thus spaced from each other.

The strands D D, coming from the supply 85 spool and tension means, extend through guide *g*, over bar *m* and rail *e* (in the notch of guide *f* thereof) to spool *d*. One or the other of the parts *m* and *e* being moved relatively to the other crosswise of the line 90 of draft on the strands, (for instance, part *e* may be reciprocated so as to perform the function usual thereto in doubling machines of laying the strands on spool *d* in coils proceeding from one end to the other thereof 95 and part *m* may be reciprocated in synchrony with part *e* but through a greater range and hence at greater speed), and the strands at the same time being drawn lengthwise by spool *d*, the result will be that 100 the portions of the strands in contact with the bar *m* will be rolled or wrapped around each other as shown in Fig. 2.

The space formed by groove C in the bar *m* has this very important advantage, to 105 wit, that the wiping action as between the strands and bar is confined to the right and left twists E E, which are the result of the wrapping or rolling of the strands around each other, and the "crown" F of the wrap 110 is left free, so that the strands at this point F may move unimpeded around and around

each other, as the wrapping proceeds, to an extent far beyond that possible where the bar is plain or ungrooved and therefore offers a positive obstacle to the strands at F 5 rolling around each other, at least when the tension has been augmented beyond a certain point by the twisting of the strands at E E. The obvious result is that it is possible by this invention to obtain a more 10 tightly wrapped product and more perfect uniformity in the degree to which the successive wrappings therein are carried than heretofore.

Having thus fully described my invention, what I claim is:

1. In combination, with means to draw the strands lengthwise, a wrap-producing member having a pair of spaced surface-ports bearing each against the strands and extending smooth in a direction transverse of 20

the line of draft on the strands, and means to effect relative movement as between said member and strands crosswise of the draft line, the space between said surface-ports being substantially coincident with the 25 crown of the wrapping formed in the strands.

2. In combination, with means to draw the strands lengthwise, a wrap-producing bar extending in a direction transverse of 30 the line of draft on the strands and being in contact therewith and having a longitudinal groove, and means to effect relative movement as between said bar and strands, said groove being substantially coincident 35 with the crown of the wrapping formed in the strands.

In testimony whereof I affix my signature.

EMORY J. LIPPS.
